(57) **CLAIM**

The ornamental design for a bounce entertainer for children, substantially as shown and described.

DESCRIPTION

FIG. 1 is a first perspective view of a bounce entertainer for children according to the design.

FIG. 2 is a second perspective view of the bounce entertainer of FIG. 1.

FIG. 3 is a front view of the bounce entertainer of FIG. 1. FIG. 4 is a back view of the bounce entertainer of FIG. 1. FIG. 5 is a first side view of the bounce entertainer of FIG. 1.

FIG. 6 is a second side view of the bounce entertainer of FIG. 1.

FIG. 7 is a top view of the bounce entertainer of FIG. 1; and, FIG. 8 is a bottom view of the bounce entertainer of FIG. 1. The broken lines in the drawings illustrate portions of the bounce entertainer for children and form no part of the claimed design.

1 Claim, 5 Drawing Sheets
